UNITED STATES PATENT OFFICE

2,586,203

VOLTAGE INDICATING INSTRUMENT AND
CASE THEREFORFrancis B. Boyle, Kalamazoo, Mich., assignor to
The Wigginton Company, Kalamazoo, Mich.,
a corporation of Michigan.

Application September 28, 1949, Serial No. 118,209

8 Claims. (Cl. 171—95)

1

This invention relates to improvements in voltage indicating instrument and case therefor.

The principal objects of this invention are:

First, to provide a novel form of voltage indicating instrument which contains and protects its test prods when not in use.

Second, to provide a voltage indicating instrument with test leads and prods which can be handled in a plurality of relationships with respect to the body of the instrument for conveniently reading the dial of the instrument while applying the prods to electrical circuits being tested.

Third, to provide a novel form of case for inexpensively retaining the operating elements and prods of a voltage indicating instrument.

Fourth, to provide a voltage indicating instrument having means therein for indicating which of two wires of a circuit is the live wire.

Other objects and advantages relating to details of my instrument will be apparent from a consideration of the following description and claims. The drawings, of which there is one sheet, illustrate a preferred form of my instrument.

Fig. 1 is an elevational view of the instrument and its prods in inactive carrying position.

Fig. 2 is a view of the instrument with one-half of the case removed.

Fig. 3 is a transverse cross sectional view taken along the plane of the line 3—3 in Fig. 2.

Figs. 4, 5 and 6 are views showing three positions in which the prods of the instrument may be positioned relative to the case.

My instrument consists of a case 1 formed of similar halves 2 and 2A which are shaped to meet along a central parting plane 3. Preferably the halves of the case will be molded from plastic material. The upper end of the case is generally rectangular while the corners of the lower end of the case are notched inwardly as at 4 leaving a central projection 5 from which the test leads 6—6 extend to a familiar type of test prod 7 having an insulating grip or handle 8.

The back half 2A of the case is shaped on its inner side with parallel half round recesses 9 extending along the sides of the case and a central recess 10 adapted to receive the lower half of a coil 11 and the movable armature 12. Attention is called to the fact that the recess 10 is enlarged intermediate of its ends providing shoulders 13 for engaging the ends of the coil and preventing longitudinal movement of the coil in the case. The upper end of the recess 10 is further notched along the bottom as at 14 (see Fig. 3) to receive a lug 15 carried on the indicator pin 16 of the

2

armature. The lug serves to guide the armature in its movement within the recess under the influence of the coil as will be explained.

The front half of the case 2 is provided with 5 half round recesses 17 mating with the recesses 9 in the back half. The recesses 9 and 11 form bores extending along the sides of the case and opening through the notched ends of the case to receive the insulating handles 8 of the test prods. 10 The front half of the case is also provided with a central recess 18 mating with the recess 10 in the back half to receive the coil and is slotted as at 19 to provide an opening for the indicator pin 16. The indicia plate 20 is secured to the front 15 half and around the slot 19 and carries voltage indicia cooperative with the pin 16.

The lower or inner ends of the central recesses 10 and 18 below the coil 11 provide space for the mounting and retension of a resistor 21 and neon lamp 22. The central recess opens through the 20 bottom of the projection 5 forming a passage for the test leads 6 which are anchored to the case by pins 23. A pair of screws 24 extending through the upper and lower ends of the case hold the two halves of the case together.

25 Within the case one of the test leads 6 is connected by a wire 25 to one terminal of the neon lamp and to one end of the resistor 21. The other test lead is connected by a wire 26 to one end of the coil 11 and the other end of the coil is connected by the wire 27 to the resistor 21. The free electrode of the neon tube is connected by a wire 28 to a small metal plate 29 lying alongside of the coil 11 but electrically insulated therefrom.

30 The theory of operation of the voltage indicating elements is well known and it will be understood that voltage applied to the test prods will be connected through the resistor and coil to attract the armature 12 inwardly of the coil against the resistance of the spring 39. The indicating pin 16 is thus caused to move along the slot 19 to the appropriate voltage indicia on the plate 20. The function of the neon lamp and plate 29 is also well understood in that if the test prod 7 connected to the neon lamp is applied 35 to a live wire while the instrument is held in inverted or faced downward position sufficient capacitance will be present between the hand of the operator and the plate 29 to cause the neon lamp to glow thus indicating that the wire is energized. A hole 30 in the back half of the case permits the lamp 22 to be viewed when the instrument is used as a hot wire indicator.

40 A particularly novel feature of my instrument is the manner in which the grips 8 of the test prods are retained in the bores along the sides

of the instrument. Annular grooves 31 are formed in the case and around the bores near the upper or outer ends thereof and springable split rings 32 are positioned in these grooves to frictionally grip the sides of the handles 8. Note that the left prod and handle as shown in Fig. 2 abuts its associated split ring and prevents the pointed prod 7 from accidentally projecting from the case. A slight but definite pressure applied to the lower end of the grip 8 will expand the split ring and permit the grip to move past the ring and project the prod from the outer end of the case as shown by the right prod in Fig. 2. If one prod is drawn completely through its bore until the split ring snaps closed behind the inner end of the grip as shown in Fig. 6 the instrument can then be held in one hand with one prod projecting therefrom for application to a wire or contact to be tested. This leaves the operator's other hand free to operate and move the other prod to various contacts as desired with the first prod and instrument held in a convenient readable position.

If both prods are pushed completely through the bores in the case the test leads may be looped upwardly through the bores as indicated in Fig. 5 permitting the operator to move the prods about to various contacts while the case of the instrument hangs in an upright position immediately in front of the operator for convenient reading of the instrument scale. Fig. 4 shows the instrument arranged for conventional handling with the test leads and prods extending freely from the base of the instrument.

Having thus described my invention, what I claim as new and desire to secure by Letters Patent is:

1. An electrical testing instrument comprising, a generally rectangular case of greater width than thickness and greater length than width, said case being formed of two parts joined along a longitudinal parting plane extending the width of the case, the meeting faces of said parts having first mating recesses formed therein and a pair of second mating recesses extending the full length of the case longitudinally alongside of said first recesses, the corners of the lower end of said case being cut away leaving a projection between the lower ends of said second recesses, a coil received in said first recesses, an armature telescopically slidable in said coil parallel to said second recesses and having an indicating finger visible through one of said parts, test leads entering said case through said projection and electrically connected to the ends of said coil, test prods secured to the outer ends of said leads and having insulating handles, said handles being axially slidably receivable and laterally retainable in said second recesses, and stops projecting into said second recesses near the outer ends thereof and adapted to engage the ends of said handles to resist the passage of said handles through said second recesses, said prods and handles being of such a length that the inner ends of said handles project from said case alongside of said projection when the ends of the prods are located within and adjacent the outer ends of said second recesses and the outer ends of the handles are abutted against said stops.

2. An electrical testing instrument comprising, a generally rectangular case of greater width than thickness and greater length than width, said case being formed of two parts joined along a longitudinal parting plane, the meeting faces of said parts having first mating recesses formed therein and a pair of second mating recesses ex-

tending the full length of the case longitudinally alongside of said first recesses, the corners of the lower end of said case being cut away leaving a projection between the lower ends of said second recesses, a coil received in said first recesses, an armature telescopically slidable in said coil parallel to said second recesses and having an indicating finger visible through one of said parts, test leads entering said case and electrically connected to the ends of said coil, test prods secured to the outer ends of said leads and having insulating handles, said handles being axially slidably receivable in said second recesses, and springable gripping elements projecting into said second recesses near the outer ends thereof and adapted to yieldably engage the ends of said handles to resist the passage of said handles through said second recesses, said prods and handles being of such a length that the inner ends of said handles project from said case alongside of said projection when the ends of the prods are located within and adjacent the outer ends of said second recesses and the outer ends of the handles are abutted against said gripping elements.

25 3. A voltage indicating instrument comprising, a case having a central longitudinal recess formed therein, voltage indicating mechanism including a coil and reciprocable armature retained in said recess, test leads electrically connected to said mechanism and extending from said case, said case having a pair of longitudinally extending bores formed therethrough along each side of said recess and parallel to said armature, test prods having insulating grips secured to the outer ends of said test leads and being axially slidably receivable in said bores, said grips being laterally retained when in said bores by the walls thereof, and annular yieldable gripping elements positioned in said bores to engage the ends of said grips and yieldably resist movement of said grips through said bores, two corners of said case being cut away along said bores and said grips being of such a length that the inner ends of said grips project into the cut away areas when the outer ends of said prods are positioned in said bores.

40 4. A voltage indicating instrument comprising, a case having a recess formed therein, voltage indicating mechanism including a coil and reciprocable armature retained in said recess, test leads electrically connected to said mechanism and extending from said case, said case having a pair of longitudinally extending bores formed therethrough alongside of said recess and parallel to said armature, test prods having insulating grips secured to the outer ends of said test leads and being axially slidably receivable in said bores, said grips being laterally retained when in said bores by the walls thereof, and annular yieldable gripping elements positioned in said bores to engage the ends of said grips and yieldably resist movement of said grips through said bores in either direction.

45 5. An electrical testing instrument comprising, a case, test leads extending from said case, said case having a pair of longitudinally extending recesses formed therein and extending from end to end thereof, test prods having insulating grips secured to the outer ends of said test leads and being axially slidably receivable in said recesses, said grips being fully laterally retained when in said recesses by the walls thereof, and stops in said recesses selectively engageable with the ends of said grips to resist movement of said grips through said recesses.

6. A case for an electrical testing instrument including mechanism for registering an electrical condition and test leads and prods for connecting said mechanism to a circuit comprising, a pair of generally rectangular parts joined together along a longitudinal parting plane, the meeting faces of said parts forming mating central recesses extending longitudinally of the case to receive said mechanism and mating recesses forming passages extending longitudinally of the case on each side thereof and opening through both ends of said case, the corners of one end of said case being notched whereby test prods on the ends of said leads may be axially slidably received and laterally retained in said passages with their inner ends projecting from the notched portions of the case while the outer ends of the prods are positioned within said passages, and stops positioned in said passages adjacent to the outer ends thereof and adapted to engage said test prods to resist movement of said prods in said passages.

7. A case for an electrical testing instrument including mechanism for registering an electrical condition and test leads and prods for connecting said mechanism to a circuit comprising, a generally rectangular body having a central recess extending longitudinally therein to retain said mechanism and longitudinally extending recesses formed therein on each side of said case and opening through both ends of said case, the corners of one end of said case being notched whereby test prods on the ends of said leads may be axially slidably received and laterally retained in said side recesses with their inner ends projecting from the notched portions of the case while the outer ends of the prods are positioned within

said side recesses, and stops positioned in said side recesses and adapted to engage said test prods to resist axial movement of said prods in said side recesses, said stops being positioned closer to the outer ends of said side recesses than the inner ends thereof whereby the inner ends of said prods may be selectively positioned in the outer ends of said side recesses and against said stops with the outer ends of said prods projecting outwardly of said case.

8. In an electrical testing instrument including mechanism for registering an electrical condition and test leads and prods for connecting said mechanism to a circuit, a generally rectangular body having a recess extending longitudinally therein to retain said mechanism and longitudinally extending recesses formed along the sides thereof and opening through both ends of said case for axial reception and lateral retention of said prods.
